UNITED STATES PATENT OFFICE.

GEORGE W. WYMAN, OF WILMINGTON, DELAWARE.

STEAM-LOCOMOTIVE.

1,091,178.

Specification of Letters Patent. Patented Mar. 24, 1914.

Application filed November 21, 1913. Serial No. 802,205.

To all whom it may concern:

Be it known that I, GEORGE W. WYMAN, a citizen of the United States, residing at Wilmington, in the county of Newcastle and State of Delaware, have invented a certain new and useful Improvement in Steam-Locomotives, of which the following is a specification.

The invention relates to devices for supplying steam in limited quantities to the cylinders of the locomotive when the latter is drifting or making a stop. Such supply is of advantage in that the cylinders are thus filled with steam and the formation of a vacuum is avoided, and is especially advantageous in locomotives using dry steam from a superheater in that such small supply also tends to prevent carbonizing the lubricant in the valves and cylinders.

In operating engines equipped with superheaters it is the common practice when drifting, to hold the throttle-valve "cracked" or in such position as to provide a small opening to allow a small amount of steam to pass through the dry-pipe to the steam-chests and cylinders, relying upon the engineer to determine the proper volume and thus adding to his many duties.

The object of the present invention is to provide simple, economical, and easily applied means, independent of the throttle, by which the desired supply of steam at low pressure will be automatically delivered to the steam-chests and cylinders of the locomotive when drifting or making a stop, without requiring the attention of the engineer, and which may be controlled and regulated to supply steam at any predetermined pressure.

The invention consists in certain novel arrangements of parts by which the above objects are attained, to be hereinafter described and claimed.

The accompanying drawings form a part of this specification and show approved means for carrying out the invention.

Figure 1 is a longitudinal section of a portion of a locomotive, partly in elevation, having a well-known form of superheater, and equipped with the invention. Fig. 2 is an elevation on a larger scale showing the connections used in applying the invention.

Fig. 3 is a front elevation of certain portions in the interior of the smoke-box of a locomotive using saturated steam and of a general type, equipped with the invention.

Similar letters of reference indicate like parts in all the figures.

Referring to Figs. 1 and 2, A is the boiler, B the dry-pipe extending through the front tube sheet A¹ and joined to the header C of a well-known type of superheater having units C² lying in the large upper tubes A² of the boiler. Steam pipes D from the header C lead superheated steam to the steam-chests D¹ and cylinders D². Within the cab A³ and located on the rear sheet or back head A⁴ of the boiler is the turret or bridge A⁵ from which extend the various steam connections, not shown, for the injector, lubricators, and other devices as usual. All these parts may be understood to be of the ordinary or any approved construction.

L is a pipe controlled by a valve L¹, leading from the turret A⁵ to a pressure reducing-valve L² adapted to be adjusted to receive steam at boiler pressure and deliver it at a greatly reduced pressure to the pipe M, preferably of larger diameter than the pipe L, and forming a continuation of the latter, leading to the inlet C¹ of the header C or to any convenient point on the header, from which the steam delivered will be led through the superheater and thence to the steam-chest D¹ and cylinder D².

By means of the pipe L steam at boiler pressure will be delivered to the reducing-valve L² at all times and the latter deliver steam at a greatly reduced pressure, as twenty five pounds for example, through the pipe M to the steam-chests when the throttle is closed and the locomotive drifting or stopped. The steam thus supplied is sufficient to fill the cylinders and valve passages and prevent carbonizing of the lubricant, and to avoid the formation of a vacuum. The operation is performed automatically and requires no attention from the engineer other than occasional inspection.

When the throttle is opened and steam at high pressure is supplied to the dry-pipe and superheater, the flow through the pipe L M ceases by reason of the back pressure produced in the pipe L M by the difference in pressures, and in order to protect the reducing-valve L² from damage due to the excessive back pressure, a check-valve M¹ is located in the pipe M and arranged to be closed by such difference in pressures.

If it be preferable to supply saturated steam to the steam-chests and cylinders, the pipe M may be connected to the header C at

the point indicated by dotted lines at c , or at any convenient point beyond the return connections of the units C^1 , and the supply of low pressure steam will thus be led directly 5 to the steam chests without traversing the superheater.

Fig. 3 shows the front end of a boiler of a common type without a superheater and with the pipe M^2 , corresponding to the pipe 10 M of the preceding figures, connected to the T -head B^1 at the junction of the dry-pipe with the steam pipes D^3 D^3 . The action in this arrangement is the same essentially as before, and the apparatus is in all respects 15 similar to that shown in Fig. 2.

It will be understood that the pipe L may be connected to the boiler at any convenient high point instead of to the turret A^4 and that the pipe M may lead to any point from 20 which its steam will reach the steam chest and cylinder.

The device is inexpensive and is easily installed on locomotives of any type.

The pipes L and M and valves L^1 , L^2 and 25 M^1 may be of any suitable construction and placed at any easily accessible or convenient locations relatively to the boiler and cab.

I claim:—

1. In a steam locomotive, a boiler, steam 30 chests and cylinders, a superheater; a dry pipe delivering steam to said superheater, steam pipes from said superheater to said steam chests, an auxiliary pipe from said boiler to said superheater, a reducing-valve 35 in said pipe, the latter and said reducing-valve arranged to receive steam at high pres-

sure from said boiler and deliver to said superheater at a reduced pressure.

2. In a steam locomotive, a boiler, steam 40 chests and cylinders, a superheater, a dry pipe delivering steam to said superheater, steam pipes from said superheater to said steam chests, an auxiliary pipe from said boiler to said superheater, a reducing-valve 45 in said pipe, and a check-valve in said pipe between said reducing-valve and said superheater, said pipe and valves arranged to receive steam at high pressure from said boiler and deliver it to said superheater at a reduced pressure.

3. In a steam locomotive having a boiler, steam chests, cylinders, and steam connections from said boiler to said steam chests, an auxiliary pipe delivering steam from said boiler to said steam chests, a reducing-valve 50 in said pipe, a check-valve in said pipe between said reducing-valve and said steam chests, and a valve in said pipe between said boiler and reducing-valve, for controlling the admission of steam to said pipe; the latter and its valves arranged to receive steam at high pressure from said boiler and deliver it to said steam chests at a reduced pressure.

In testimony that I claim the invention above set forth I affix my signature, in presence of two witnesses.

GEORGE W. WYMAN.
